UNITED STATES PATENT OFFICE.

HENRY J. MAUGER, OF SCHENECTADY, NEW YORK, ASSIGNOR TO GENERAL ELECTRIC COMPANY, A CORPORATION OF NEW YORK.

ELECTRIC HAIR-DRIER.

1,006,767.

Specification of Letters Patent. Patented Oct. 24, 1911.

Application filed January 19, 1910. Serial No. 538,802.

To all whom it may concern:

Be it known that I, HENRY J. MAUGER, a citizen of the United States, residing at Schenectady, county of Schenectady, State 5 of New York, have invented certain new and useful Improvements in Electric Hair-Driers, of which the following is a specification.

This invention relates to electric hair driers and the like and has for its object the provision of a device whereby the electric current may be employed for the purpose of quickly drying the hair, in a reliable and efficient manner. In devices of this 10 character, as generally constructed, it is customary to employ a fan or blower in connection with an electric heater. The fan blows a current of air over the heater with the idea of increasing the hygroscopic value 15 of the air by warming it. This is a very inefficient application of electric energy. In order to render the device more efficient, I combine the mechanically driven blast of air with heat energy in the radiant form. 20 A high temperature source of heat is arranged so as to reflect the heat upon the hair directly and the current of air is then blown upon the hair at the point where it is heated.

In the ordinary forms of electric hair 25 driers, heat in convective form is delivered to the hair and a large part of it is ineffective in absorbing the moisture of the hair, since it passes off into the room and is wasted. This is not true of my device, since 30 the radiant heat is not affected by the current of air. The air absorbs practically no radiant energy and therefore the heat from the radiant source being entirely concentrated on the hair is of very high efficiency 35 and no loss will result from the passing away of heat in air currents.

In the accompanying drawing, in which 40 I have shown my invention embodied in concrete form for purposes of illustration, 45 Figure 1 represents one form of my invention; and Fig. 2 represents a modified form with the motor and fan broken away.

Referring to the drawings, 10 represents 50 a fan or blower on the shaft 11, driven by

an electric motor 12. The particular arrangement of the fan and the motor forms no part of my invention. The fan is surrounded by a casing 13 which affords a passageway 14 for the current of air. Mounted in the passageway is a bracket 15 supporting the lamp socket 16 into which an incandescent lamp 17 is fitted. The reflector 18 is secured to the socket and is so arranged as to deflect the heat outward. The passageway 14 is enlarged at 19 around the reflector 18 so as to leave an annular passage between the reflector and the casing 19. The casing 19 and reflector 18 are extended a short distance beyond the lamp 17, but not so far as to prevent the lamp from being placed 55 close to the point of application of the heat and air. The conductors 20 to the motors and lamp pass through the handle 21. When the lamp 17 is placed close to the head the hair is heated and the current of 60 air is blown on the head. This makes a very effective and efficient arrangement for drying the hair and lends considerable comfort to the person operated upon.

In the form shown in Fig. 2 the air is 65 blown directly over the electric lamp through the passage 22; that is, the casing 19 acts as a reflector for the heat, otherwise the arrangement is the same as that shown in Fig. 1.

While I have described my invention as embodied in concrete form for purposes of illustration, it should be understood that I do not limit my invention to the particular construction and arrangement of parts 75 80 85 therein shown, since various modifications thereof will suggest themselves to those skilled in the art without departing from the spirit of my invention, the scope of which is set forth in the annexed claims. 90

What I claim as new and desire to secure by Letters Patent of the United States, is:—

1. An electric hair drier comprising an electric motor, a fan driven thereby, a source of radiant heat, and a reflector arranged to 95 direct the heat on the surface of impact of air from the fan.

2. An electric hair drier comprising an

electric motor; a fan driven thereby, an electric heater arranged to be held in close proximity to the point of application, and means for reflecting the heat in the direction of the current of air from the fan.

3. An electric hair drier comprising an electric motor, a fan driven thereby, an incandescent lamp, and a reflector arranged

to direct the heat from the lamp in the direction of the current of air from the fan. 1

In witness whereof, I have hereunto set my hand this 17th day of January, 1910.

HENRY J. MAUGER.
